MACHINE FOR ASSEMBLING, SECURING, AND BANDING PACKAGES

William H. Giles, Brooklyn, and Anton Richard Frank, Jamaica, N.Y., assignors, by mesne assignments, to Van Buren Machine Corp., Brooklyn, N.Y., a corporation of New York

Filed Aug. 27, 1958, Ser. No. 757,563

8 Claims. (Cl. 53—159)

This invention relates to wrapping machines and particularly to a machine for banding articles into a stack and to a machine for applying adhesive to the wrapped articles so banded.

At the present time it is common practice to sell articles, such as bars of soap, in a pack or stack having several bars or cakes packaged together. Moreover, it is common practice to assemble a plurality of bars and to wrap a band around the assembled bars. It has been found that when so wrapped the inner cakes become loose and are dropped out.

This invention has for its object to provide means for spotting or applying adhesive on the inner bars of a stack of bars to prevent their becoming loose and dropping out of the package.

Further objects of the invention will appear from the following specification taken in connection with the drawings which form a part of this application, and in which:

Fig. 1 is a side elevation of a machine constructed in accordance with the invention;

Fig. 2 is a sectional elevation, on an enlarged scale, taken substantially on line 2—2 of Fig. 1, looking in the direction of the arrows;

Fig. 3 is a detail elevation view, broken away, but showing one of the bars or cakes in contact with the glue spotting or applying means;

Fig. 4 is a view similar to that shown in Fig. 3 but in which no glue or adhesive is applied;

Fig. 5 is a detail elevational view showing the means for engaging and moving a plurality of assembled articles which have been discharged from the apparatus for applying adhesive thereto to a table from which they are moved to banding mechanism;

Fig. 6 is a diagrammatic elevation showing the path taken by the assembled articles from the adhesive applying machine to the banding apparatus;

Fig. 7 is a diagrammatic elevational view showing the apparatus for applying the securing band around one end and two sides of the stack of assembled articles; and

Fig. 8 is a perspective view illustrating the banded package of assembled articles or bars.

The invention may be briefly described as follows. The wrapped articles, such as bars of soap, are fed one at a time to clamps which are mounted on a rotating carrier, the carrier having at properly spaced intervals on the periphery thereof, adhesive applying means which engages the side surface of certain of the articles to be assembled into a stack. The adhesive is applied to the said surface of certain of the articles before the articles are clamped and fed around the periphery of the machine. It is obvious that adhesive is not applied to the inner surfaces of the outer article of the stack. In other words, if the stack consists of four articles, three of the articles will have adhesive applied thereto, thus securing them together prior to and after banding.

From the rotary machine carrying the clamps, the articles are discharged to a table and are pressed to-

2

gether on the table, thus securing the inner articles against dislodgment, and thereafter the stack of assembled articles, such as four, are discharged laterally from the table to another table from which they are fed through banding mechanism.

Further details will appear from the following description.

In the particular embodiment of the invention illustrated in the drawings, the machine is mounted on a frame 10 and the adhesive applying mechanism is shown particularly in Fig. 1 and will be first described.

This mechanism consists of a pair of parallel disks or plates 11 and 12, which are mounted on a shaft 13 having secured thereto a gear 14 driven by a chain 15 from any suitable source of power.

The disks 11 and 12 are mounted in spaced relation and each disk has pivotally mounted thereon, as shown at 20, a plurality of clamps 21, between which the articles, such as the cakes or bars, are clamped.

Each clamp 21 has a post 25 having a bifurcated yoke 26 in which is mounted a roller 27. Furthermore, each clamp 21 has secured thereto, as shown at 30, a tension spring 31, the other end of the spring being secured to the disk 11 or 12. Thus the spring 31 tends to move the clamp inwardly into operative position to clamp the cake or bar therebetween.

Each clamp or clamping jaw also has secured thereto a post 32 having an adjustable stop 33 and an end 34 which extends through an opening 35 in the disk 11 or 12. The clamp is thus guided and limited in its movement.

In order to control the inner and outer movement of the clamp or clamping jaws 21, a cam 40, suitably designed, is positioned in the path of movement of the rollers 27 and thus causes the clamps to engage and clamp the articles fed along a platform 41 and, further, causes the clamps to release the articles when they are disposed in a position 180° from the position at the platform 41 or as indicated at 42 in Fig. 1.

In order to apply adhesive to the inner surfaces of the bars A, B and C in the stack of four bars, as shown in Fig. 7, adhesive applying pads 50 are mounted between the disks 11 and 12 and as the disks are rotated around the axis of the shaft 13 the pads contact the adhesive roller 51 which picks up adhesive from the vat 52. It will be noted that the adhesive applying pads are equally spaced in groups of three and that after the third pad, in the direction of rotation of the disks, one pad is omitted before the next group of three appear.

The articles, such as bars of soap, which have been previously wrapped, are fed along the platform 41 and the end article X in Fig. 1 has received adhesive when the pad 50A has contacted it before the article X has been picked up by the clamps and fed with the disks. Moreover, the article Y has also received adhesive from the pad 50B. The next article Z will receive adhesive from the pad 50C but the article after the article Z will not receive any adhesive since the position indicated at D in Fig. 1 has no adhesive pad located thereat.

After the articles have received adhesive as above described and have moved from the position at the platform 41 or at the right in Fig. 1 to the position indicated at 42, or through 180° of movement, the articles are discharged by a bifurcated pusher arm 55, which extends at right angles to an arm 56 pivoted to arms 57 and 58 mounted on fixed pivots 59 and 60. The arm 57 has pivoted thereto a link or pitman 61 having a bifurcated end 62 which straddles a shaft 63 on which is mounted a cam 64. The end 62 of the pitman 61 has a roller 65 engaged by the cam and the cam operates to reciprocate the link or pitman 61, thus actuating the arm 55 and removing the articles from be-

tween the clamping jaws 21, 21. It will be understood that the jaws are so controlled by the cam 40 that they will release the articles when they are disposed in the position shown at 42.

The articles thus discharged are moved to a table or support 70 and are held on the support by a spring pressed plate 71. The articles thus moved to the support will move successively along the support in the direction of the arrow shown in Fig. 6.

Assuming that the articles are to be assembled in groups of four, the group of four at the end of the table which has moved against a stop 72 will be moved laterally in the manner shown in Figs. 5 and 6.

From the showing in Figs. 1, 5 and 6, it will be noted that a pair of conveyors or chains 80 and 81 are mounted on a spindle 82 supported in bearings 83 and 84 and uprights 85 and 85, the chains and shaft being disposed above the table 70 and above the group of four articles limited in their movement by the stop 72.

The chains 80 and 81 have mounted thereon a plurality of pivoted pusher plates 90 which have extending at right angles thereto bars 91 on the outer end of which are mounted rollers 92. The rollers engage a stationary cam surface 93 and move the plates into discharging position as shown in Fig. 5.

The plates 90 are sufficiently wide to engage the group of articles to be discharged or moved at right angles, and Fig. 6 shows diagrammatically how the articles are moved along an extension or a second supporting table 94. After the group at the right has been moved against a stop 95 it is engaged by a pusher 96 and moved from the platform 94 to a discharge platform 100. Between the platforms 94 and 100 a banding strip 101 is fed by rollers 102 and is cut by a knife 113. This strip is engaged by the group of assembled articles and the band is folded around the advanced end and upper and lower sides of the assembled articles to the position shown in 101A in Fig. 7. The band 101 is provided with suitable adhesive or heat sealing material, which is effectively secured to the outer surfaces of the articles between sealing plates 103 and 104.

In order to effectively illustrate the adhesive spotted on the faces of the bars or cakes, the adhesive is shown in exaggerated form in Fig. 7 at 110, 111 and 112. Fig. 8 shows the banded articles and because of the adhesive spotted on the faces of the articles at 110, 111 and 112 the inner articles will not drop out of the stack of the banded articles.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What we claim is:

1. In a machine for spotting adhesive on the inner faces of articles to be assembled in a stack comprising a rotary supporting member, a plurality of clamps radially mounted on said member, adhesive pads mounted on the periphery of said member, a support for conducting articles to the periphery of the member in position to receive adhesive from said pads and to be engaged by said clamps, means for operating the clamps at the receiving position opposite the support, and means for opening the clamps at the discharging positions thereof.

2. In a machine for spotting adhesive on the inner faces of articles to be assembled in a stack comprising a rotary supporting member, a plurality of clamps radially mounted on said member, adhesive pads mounted on the periphery of said member, a support for conducting articles to the periphery of the member in position to receive adhesive from said pads and to be engaged by said clamps, means for operating the clamps at the receiving position opposite the support, means for open-

ing the clamps at the discharging positions thereof, a support for receiving the discharged articles, means for moving the articles from the support in a stack and means for wrapping a band around one end and two sides of the stack.

3. In a machine for spotting adhesive on the inner faces of articles to be assembled in a stack comprising a rotary supporting member, a plurality of clamps radially mounted on said member, adhesive pads mounted on the periphery of said member between certain of said clamps, a support for conducting articles to the periphery of the member in position to receive adhesive from said pads and to be engaged by said clamps, means for operating the clamps at the receiving position opposite the support, and means for opening the clamps at the discharging positions thereof.

4. In a machine for spotting adhesive on the inner faces of articles to be assembled in a stack comprising a rotary supporting member, a plurality of clamps radially mounted on said member, adhesive pads mounted on the periphery of said member between certain of said clamps, certain of the spaces between the clamps having no adhesive pads thereon, a support for conducting articles to the periphery of the member in position to receive adhesive from said pads and to be engaged by said clamps, means for operating the clamps at the receiving position opposite the support, and means for opening the clamps at the discharging positions thereof.

5. A machine for spotting adhesive on the faces of articles to be assembled in a stack comprising a movable supporting member, a plurality of clamps mounted in spaced relation on said member, adhesive pads mounted on said movable member between certain of said clamps, the spaces between certain of said clamps having no pads mounted therein, a support for conducting articles to the path of movement of said supporting means and clamps, means for closing the clamps at the receiving position opposite said support, and means for opening the clamps at the discharging positions thereof.

6. In a machine for applying adhesive to the inner articles of a stack of completely wrapped articles assembled for banding together, a support for wrapped articles to which adhesive is to be applied, adhesive applying means for applying adhesive to a surface of certain wrapped articles when they are disposed at the delivery end of the stack, means for moving said means into contact with the outer surfaces of the wrapped articles, and subsequently acting, oppositely moving, clamping means for gripping and moving the articles, one at a time, to discharge position.

7. In a machine for applying adhesive to the inner articles of a stack of completely wrapped articles assembled for banding together, a support for wrapped articles to which adhesive is to be applied, adhesive applying means for applying adhesive to a surface of certain wrapped articles when they are disposed at the delivery end of the stack, means for moving said means into contact with the outer surfaces of the wrapped articles, subsequently acting, oppositely moving, clamping means for gripping and moving the articles, one at a time, to discharge position, and means for discharging the articles, one at a time, to a supporting table to assemble and stack the articles in successive contact with each other.

8. In a machine for applying adhesive to the inner articles of a stack of completely wrapped articles assembled for banding together, a support for wrapped articles to which adhesive is to be applied, adhesive applying means for applying adhesive to a surface of certain wrapped articles when they are disposed at the delivery end of the stack, means for moving said means into contact with the outer surfaces of the wrapped articles, subsequently acting, oppositely moving, clamping means for gripping and moving the articles, one at a time, to discharge position, means for discharging the articles, one at a time, to a supporting table to assemble and stack the articles in successive con-

tact with each other, and means for banding the articles thus assembled into a stack.
